UNITED STATES PATENT OFFICE.

MATHILDA W. OTT, OF COEUR D'ALENE, IDAHO.

TEMPORARY HAT-LINING.

1,247,319.

Specification of Letters Patent. Patented Nov. 20, 1917.

Application filed July 5, 1917. Serial No. 178,742.

To all whom it may concern:

Be it known that I, MATHILDA W. OTT, a citizen of the United States, residing at Coeur d'Alene, in the county of Kootenai 5 and State of Idaho, have invented certain new and useful Improvements in Temporary Hat-Linings, of which the following is a specification.

The present invention relates to an improved temporary hat lining and is designed particularly for use in hat stores, millinery establishments, and similar places where ladies hats are "tried on" by a prospective customer. The primary object of the invention is the provision of a sanitary lining in the shape of a cap, to be worn by the prospective customer during the process of trying on new hats, in order to prevent soiling or marring the new hat, which would otherwise be the case, when the new hat comes in contact with the wearers who successively try it on. In this manner the appearance of the hat is maintained in a fresh, unsoiled condition, and the transmission of disease 20 or germs from one person to another is prevented because of the fact that the sanitary lining may be, and is designed to be, washed or cleansed after each individual use.

In the accompanying drawings I have illustrated two forms of the invention as they have been physically embodied and in actual use, and these are the best modes I have so far devised for the practical application of the principles of my invention.

Figure 1 is a view in vertical cross section of a lady's hat showing the temporary lining therein in the position for use.

Fig. 2 is a bottom plan view of the hat and lining of Fig. 1.

Fig. 3 illustrates another form of the invention, involving a bandeau construction, parts being in section.

Fig. 4 illustrates one of the resilient adjustable rings of the lining construction.

The lining as has been made for actual use is illustrated in the drawings in the form of a cap, the material used being preferably of oil silk, or other water-proof material that may be cleansed at frequent intervals, 45 as between times of using. The crown 1 is of usual shape and provided with a resilient adjustable wire ring, as 2, which in Fig. 4 is

illustrated as having its two ends looped over its body so that the ring may be distended or compressed to adjust to different sizes. The ring is stitched in the body of the material forming the crown, at its base, and below the base of the crown a flaring extension is provided, as indicated at 3. The edge of the extension is also provided with a resilient, adjustable wire ring 4, sewed in a hem at the extreme edge of the lining, the ring 4 being of greater diameter than the ring 3.

In Figs. 1 and 2 the utility of the lining is illustrated wherein the crown of the lining projects up inside the crown 5 of the hat, and the flaring extension lies up snugly and close to the inner edge of the brim 6 of the hat. The crown of the lining of course protects the crown of the hat from contact with the hair of the person trying it on, but particular attention is called to the protection at the juncture of the base of the hat crown and the brim of the hat afforded by the flaring extension, which comes in contact with the hair of the wearer and entirely removes the hat brim from contact with the hair.

In addition to the flaring extension, the lining may also be fashioned with an inwardly projecting annulus or bandeau 7, located in the crown and adapted to rest upon the coiffure, and in Fig. 3, the extension 3^a is shown protecting the brim of the hat as in Fig. 1. The resilient adjustable rings are indicated at 8, 9, and 10, in Fig. 3, and the lining is adjustable for different sizes or shapes of coiffure or head dress. The use of the bandeau eliminates the necessity for building up the interior of the hat which would otherwise be the case in fitting the hat to different wearers when trying them on.

What I claim is:—

A temporary hat lining of flexible, washable, material comprising a crown portion and a resilient ring at the base of the crown, an inwardly projecting bandeau inside the crown above the base and provided with a resilient ring in its free edge, a flaring extension projecting from said base and a resilient ring hemmed in the outer edge of said extension.

In testimony whereof I affix my signature.
MATHILDA W. OTT.
